UNITED STATES PATENT OFFICE.

CHARLES B. WAGONER, OF ROCHESTER, NEW YORK.

CHIMNEY CAP.

Application filed September 16, 1921. Serial No. 501,118.

To all whom it may concern:

Be it known that I, CHARLES B. WAGONER, a citizen of the United States, residing at Rochester, in the county of Monroe and State of New York, have invented certain new and useful Improvements in Chimney Caps, of which the following is a specification.

My invention relates to chimney caps, and 10 has for its purpose to afford a practical and durable construction adapted to be readily and firmly positioned on a chimney and to serve, in general, more satisfactorily than caps now in use for the same purpose.

15 A more specific object of the invention is to provide a cap of minimum weight, so that it can be constructed economically and readily transported to wherever it is to be used.

20 A further purpose of the invention is to afford a construction which, while of light weight and simple construction, nevertheless lends itself readily to a firm, rigid connection with the chimney, so that it cannot be accidentally removed by high winds or other- 25 wise.

Still an additional object of the invention 30 is to afford a construction that accomplishes all of the purposes above set forth, and which also effectually prevents rain accumulating 35 on the chimney cap from reaching the side walls of the chimney underneath the cap, thus preventing the side walls of the chimney from being streaked or discolored, and the mortar between the bricks from disintegrating, by water running down from the 40 cap.

The invention also comprehends certain 45 other advantages and detailed improvements, all of which will appear clearly from the following description, in conjunction with the accompanying drawing, the novel features being pointed out in the claims following the specification.

In the drawing:

46 Figure 1 is a perspective view of a chimney, showing the application of a preferred embodiment of my invention, appearing partly in section, and

50 Figure 2 is a transverse sectional view through the chimney and cap.

The device herein disclosed comprises an integral or one-piece cap adapted to rest upon the uppermost layer of bricks forming the chimney 1. The cap is preferably formed of glass, terra cotta, porcelain, shale clay, or other similar non-conducting material, pref-

erably vitrified and glazed on its outer surface, and its walls have a cross sectional form of inverted U-shape, consisting of the horizontal portion 2 and the depending legs 60 3 and 4. This arrangement permits manufacturing a cap of the required strength and efficiency, while at the same time of such light weight as to enable readily shipping or transporting it and placing it in position 65 on a chimney.

Although a chimney cap is usually attached by mortar, it is nevertheless essential that it be locked in place against lateral displacement, and to accomplish this, I provide 70 a depending flange, or flanges, 5 on the outer legs 4, and preferably coextensive with the outer surface of the cap. The flange 5 is adapted to overlie the sides of the chimney, and thus, after it is once positioned, there is 75 no chance of accidental lateral displacement of the cap, and its firm attachment to the chimney is assured.

In order to prevent rain passing from the cap to the side walls of the chimney, I provide in the lower face of the flange 5, a longitudinally extending centrally arranged drip groove 6, which is preferably semi-circular in cross section. The drip groove 6 catches any water that would otherwise find 80 its way across the bottom of the flange 5, and traps it, so that such water falls to the ground from the groove 6 without reaching the side walls of the chimney. The life of a chimney is increased substantially by this 85 construction, because there is little likelihood of water settling in and destroying the mortar between the bricks of the chimney. Moreover, the proper appearance of the chimney 90 is preserved, as it cannot be discolored by 95 dripping rain water.

The construction described is exceedingly simple and durable, economical to manufacture and can be readily applied to any chimney, as the caps will be made in certain 100 standard sizes to fit the different standard sizes of chimneys. By forming the cap hollow, and of inverted U-shape, I am able to obtain a very light weight structure, which is of tremendous importance in shipping and positioning chimney caps, and this arrangement also lends itself with great facility to locking the cap upon the chimney against lateral displacement, through the depending flange formed upon the outer leg 105 of the inverted U-shaped wall.

While I have described a specific embodi-

ment of the invention, the improvement is not limited to the particular details disclosed, but may be modified in various respects without departing from the underlying features of the invention, and the application is intended to cover any modifications coming within the scope of the invention and of the following claims.

I claim:

- 10 1. As an article of manufacture, a light weight one-piece chimney cap comprising hollow walls of inverted U-shaped cross section, the legs of which overlie the top of a chimney.
- 15 2. As an article of manufacture, a light weight one-piece chimney cap comprising hollow walls of inverted U-shaped cross sec-

tion, the legs of which overlie the top of a chimney, the outer legs of said walls having flanges which overlie the sides of a chimney 20 and prevent lateral movement of the cap.

3. As an article of manufacture, a one-piece chimney cap comprising walls of inverted U-shaped cross section, the legs of which are adapted to rest on the upper edge 25 of a chimney, and a continuous flange adapted to overlie the sides of a chimney and prevent lateral movement of the cap, said flange having a longitudinally extending drip groove formed centrally therein.

In witness whereof, I have hereunto signed my name.

CHARLES B. WAGONER.
